UNITED STATES PATENT OFFICE.

ALMOND W. CLEVELAND, OF SHERBROOKE, QUEBEC, CANADA, AND OLIVER C. MORSE, OF STONEHAM, MASSACHUSETTS, ASSIGNORS TO WILLIAM ALBERT STUBBS, OF SHERBROOKE, CANADA.

RACK.

Application filed February 1, 1928. Serial No. 251,094.

This invention relates to a drying rack for clothes or the like such as is suitable for domestic use, and more particularly to a rack of a type which may be lowered to a convenient level to receive articles to be hung thereon or raised so as to be out of the way or to elevate the articles to be dried to the warmer layers of air near the top of a room. It is an object of the invention to provide means for efficiently controlling the descent of such a rack and for safeguarding the rack from falling in case of failure of the hoisting means. The rack may be mounted according to the invention upon a suitable carriage which travels up and down on a track member, the carriage and rack being hoisted by a cable which is operated by a hand windlass, a jamming mechanism being mounted on the rack to move into jamming engagement with the track member in case of failure of the hoisting gear. The descent of the carriage and rack may be further controlled by a braking mechanism associated with the windlass and operable by motion of a lever arm which also carries a pawl cooperating with a ratchet associated with the windlass. These parts are so arranged that motion of the lever arm to release the ratchet also applies the brake to the windlass. Conversely, motion of the lever arm to release the braking mechanism also engages the pawl with the ratchet. Further advantageous features of the invention will be apparent to one skilled in the art from the description which follows and from the drawings, of which,—

Figure 1 shows in perspective the apparatus as a whole in its normal position assumed when properly mounted on a wall.

Figure 2 is a side elevation of the apparatus, a portion being broken away to show the relation of some of the parts.

Figure 3 is a front elevation of the same.

Figure 4 is a plan view of the windlass and the mechanism associated therewith.

Referring to the drawing in detail, 10 represents a normally upright track member which may be secured to a wall as by suitable brackets 11, 12 which are so arranged as to hold the track member 10 suitably spaced from the wall. On the track member is mounted a carriage 13 which is movable up and down thereon. In order to facilitate the motion of the carriage 13 on the

track 10, a pair of rollers may be carried by 55 the carriage to bear against the track, an upper roller 14 being mounted to bear against the rear face of the track and a lower roller 15 bearing against the front face thereof. Supported by the carriage and extending forwardly therefrom are a plurality of rack arms 16, each of which may be pivotally mounted as by pins 17 to a supporting member 18 which in turn may be pivotally mounted as at 19 with the carriage 13. The pins 17 permit horizontal swinging of the arms 16 but do not permit the individual arms to drop to a vertical position. The rack as a whole, however, being pivoted on a horizontal pin 19 may be 60 swung down at will to hang vertically and to avoid collecting dust on the arms 16 when the rack is not in use. In order to maintain the rack horizontally when in use, a locking pin 20 may be provided extending 65 through a pair of ears 21 formed on the carriage, which ears also support the pivot pin 19. The locking pin 20 may be manipulated as by a thumb piece 22 and may be held in place by a cotter pin 23 or other suitable means. In order to raise and lower the carriage and rack, a suitable cable 24 may be provided, this cable being passed over a sheave 25 and brought down to a suitable windlass 26. The latter may be conveniently 70 operated as by a crank arm 27 and handle 28. As shown the sheave 25 is mounted on the upper bracket 11 and the windlass 26 is carried by the lower bracket 12. A suitable eye 29 or other equivalent means may 75 be provided on the windlass to secure an end of the cable 24. In order to hold the carriage and rack at various heights, a ratchet 30 may be provided, this ratchet 80 preferably being formed on the rim of one of the side members of the windlass 26 as shown. Cooperating with this ratchet is a pawl 31 which may be carried by a suitable lever arm 32 pivotally mounted at an end thereof as at 33 at any convenient point on the track member 10 or the bracket 12. At the opposite end of the arm 32 a handle 34 may be provided for manipulation of the lever arm 32. As shown, the pawl 31 is arranged to engage the upper portion of 85 the periphery of the ratchet. When the rack is filled with clothes or other articles to be dried, it may have considerable weight 90

and it is sometimes awkward to lower such a heavy rack by backing down with the windlass 26. In order to facilitate and control the lowering of the rack and carriage, 5 a brake drum 35 may be mounted on the windlass to rotate therewith, a suitable brake band 36 being passed around beneath the brake drum and secured at suitable points to the lever arm 32. The brake band 36 is 10 thus arranged to engage the drum at a point diametrically opposite to the pawl 31. As is obvious from the showing in Figure 3, motion of the lever arm 32 upwardly to disengage the pawl 31 from the ratchet 30 also 15 applies the brake band 36 to the drum 35 so that by pressing upwardly on the handle 34, the brake may be applied as strongly as desired to check the descent of the carriage and rack. In like manner, when the lever arm 32 is lowered to engage the pawl 31 with the ratchet, the brake is simultaneously released. If desired, the brake band 36 may 20 be mounted on the arm 32 in such a way as to be adjustable in length so that the distance interval between the point of clearance of the pawl from the ratchet teeth and the point of application of the brake band to the drum may be adjusted as desired.

In order to prevent the carriage and rack from falling to the lower end of the track member in case the cable 24 breaks or becomes unfastened or in case the hoisting apparatus fails in any other way, an automatic jamming device may be provided 30 comprising a jamming member 37 which as shown is pivotally and eccentrically mounted as at 38 to a pair of ears 39 formed on the carriage 13 and extending forwardly therefrom. The jamming member 37 is provided 35 with an arm 40 at the outer end of which the cable 24 may be attached. If desired, a fair-leader 41 may be formed on the carriage 13 for the cable 24, the arrangement being such that when the cable takes the 40 weight of the carriage and rack, it will hold the jamming member 37 in an inoperative position. A weak spring 42 may be mounted in such a way as to tend to swing the jamming member 37 to operative position, 45 the latter position being shown in dotted lines in Figure 2. By reason of its eccentric mounting, the jamming member 37 when in inoperative position is clear of the track member 10, but when allowed to move to operative position, a portion thereof swings against the forward face of the track and cooperates with the roller 14 to clamp the 50

carriage to the track and to prevent further descent thereof in case of failure of any part of the hoisting apparatus. It will be 60 obvious from Figure 2 that the arrangement of the jamming member 37 is such that the heavier the carriage and rack, the more tightly will the jamming member clamp the carriage to the track member when in operative position. 65

Having thus described certain embodiments of this invention, it should be evident to those skilled in the art that various changes and modifications may be made 70 therein without departing from its spirit or scope as defined by the appended claims.

We claim:—

1. Apparatus of the class described, comprising an upright member, a pair of brackets adjacent the ends thereof adapted to support said member in spaced parallel relation to a wall, a carriage movable up and down on said member, a drying rack attached to said carriage and movable therewith, means for hoisting said carriage comprising a sheave mounted at the upper end of said member, a windlass mounted at the lower end of said member, a flexible element attached to said carriage and extending through said sheave to said windlass, a ratchet and brake drum secured to and rotatable with said windlass, and a lever having a pawl associated with said ratchet, said windlass, ratchet and pawl being operable to elevate said carriage and to hold said carriage at various elevations, a brake band attached to said pawl and movable into braking engagement with a substantial proportion of the periphery of said brake drum when said pawl is moved clear of said ratchet, and means associated with said flexible element for preventing descent of said carriage upon failure of said hoisting means. 100

2. Apparatus of the class described, comprising a windlass, a ratchet and a braking drum coaxially secured thereto, a lever arm, and a pawl and a brake band carried by said arm and arranged to engage the ratchet and drum respectively at diametrically opposite points, the arrangement being such that motion of said arm to disengage the pawl from the ratchet applies the brake band to the drum. 110

In testimony whereof we have affixed our signatures.
